UNITED STATES PATENT OFFICE.

EDGAR G. ANTHONY, OF NEW YORK, N. Y.

CALENDAR.

1,324,330.

Specification of Letters Patent.

Patented Dec. 9, 1919.

Application filed February 9, 1918. Serial No. 216,313.

To all whom it may concern:

Be it known that I, EDGAR G. ANTHONY, a citizen of the United States, residing at New York, in the county of New York and 5 State of New York, have invented certain new and useful Improvements in Calendars, of which the following is a specification.

This invention relates to a calendar in which the data are simply and conveniently 10 assembled.

10 This invention has for its object the production of a calendar in which the data showing the days of the weeks, the months of the years, and years are arranged so as to facilitate the ascertainment in advance of 15 any date.

For a clearer understanding of the invention, reference is made to the accompanying drawings, in which—

20 Figure 1 is a plan view of a calendar showing one method of presenting the calendar-data.

Fig. 2 is a side view of the same.

25 Fig. 3 is a plan view showing another method of presenting the calendar-data.

As shown in Figs. 1 and 2, the calendar comprises a circular disk 1 on which the data hereinafter described, is assembled, pivotally attached to a backing-piece 2, a 30 leg 3 attached to the backing-piece 2 and supporting the same, and a day indicator 4 attached to the backing-piece 2. As shown in Fig. 1, the seven days of the week are assembled around a seven-pointed star. Between 35 consecutive points of the star extending radiatingly are number-columns 6, 7, 8, 9, 10, 11 and 12, at the outer extremities of which are the years corresponding thereto. Adjacent to number-column 6 are assembled 40 in radiating column-form 21, the months of the year. The particular arrangement of the data is shown for all the days of the week, the appropriate data for one day only, Sunday, being filled in. In the form of 45 calendar presented, days of particular importance may be shown on the interior of the star, and as an example of such, Easter Sunday is given for seven consecutive years.

As shown in Fig. 3, the data are assembled in a form convenient to be used as a wall-calendar. Taking Sunday as an example, the dates for all Sundays in 1917 are assembled in column 13, for 1918 in column 50 14, and so on. The months of the year are assembled in column-form 20 adjacent the number-column 19. At the head of each

number-column is arranged the year corresponding thereto.

The facility with which any particular date can be determined is illustrated by the 60 following example: Suppose it is desirable to know the date of the fourth Sunday in April, 1918. Referring to Fig. 1, the disk 1 is rotated until the day Sunday swings beneath the day-indicator 4. Turning to the 65 month-column 21, the month April is located and on a line therewith in the number-column 7 corresponding to the year 1918, the number 28 corresponding to the day aforesaid. 70

The calendar as presented is known as a seven-day seven-cycle calendar, the data being assembled for seven years. Each year a new calendar may be issued, the calendar 75 always containing the data for seven years.

The data as arranged presents an easy, simple and convenient method for determining the date of any day in advance that is within the compass of the calendar, and is of the greatest help to business firms desiring 80 such information quickly.

The data assembled in Fig. 3 instead of being in the form of a wall-calendar may be bound in book-form, each page containing one day of the week. Assembled in this 85 manner it may be easily and conveniently carried about in a person's pocket, being always at his command when needed.

I claim:—

1. A calendar having marked thereon 90 seven areas, one for each day of the week, each area divided into columns, one for each of a number of years, each column having spaces for day-of-the-week dates, and having thereon appropriately arranged designations for years, months and days of the week.

2. A calendar having marked thereon 100 seven sector-shaped areas, one for each day of the week, each area divided into columns, one for each of a number of years, each column having spaces for day-of-the-week dates, and having thereon appropriately arranged designations for the years, months and days of the week. 105

3. A calendar comprising a rotatably supported disk having marked thereon sector-shaped areas, one for each day of the week, each divided into columns, one for each of a number of years, each column having spaces 110 for day-of-the-week dates, and having thereon appropriately arranged designations

for the years, months and days of the week and an indicator fixed to the disk support.

4. A calendar having marked thereon seven sector-shaped areas, one for each day of the week, each area divided into columns, one for each of a number of years, each column having spaces for day-of-the-week dates, appropriately arranged designations for the years, months and days of the week 10 within said areas and special day spaces on the area inclosed by said sector-shaped areas.

5. A calendar having marked thereon seven sector-shaped areas, one for each day of the week, each area divided into columns, 15 one for each of a number of years, the year designations being at the outer extremities of said columns, each column having spaces for day-of-the-week dates and having thereon appropriately arranged designations for 20 the months and days of the week.

In testimony whereof I affix my signature.

EDGAR G. ANTHONY.
